DESIGN FOR A DRAFTING RADIUS TEMPLATE

Cyrus M. Riddell, Whittier, Calif.

Application November 16, 1943, Serial No. 111,705

Term of patent 7 years

To all whom it may concern:

Be it known that I, Cyrus M. Riddell, a citizen of the United States, residing at Whittier, in the county of Los Angeles and State of California, have invented a new, original, and ornamental Design for Drafting Radius Template, of which the following is a specification, reference being had to the accompanying drawing forming part thereof,

Fig. 1 is a plan view of the drafting radius template employing my new design; Fig. 2 is an edge view in elevation of the same.

I claim:

The ornamental design for a drafting radius template, as shown.

CYRUS M. RIDDELL.
